UNITED STATES PATENT OFFICE.

ELMER A. SNELL, OF LA FARGEVILLE, NEW YORK.

PAIL-HOLDER.

1,157,353.

Specification of Letters Patent.

Patented Oct. 19, 1915.

Application filed January 19, 1915. Serial No. 3,148.

To all whom it may concern:

Be it known that I, ELMER A. SNELL, a citizen of the United States, residing at La Fargeville, in the county of Jefferson, State of New York, have invented certain new and useful Improvements in Pail-Holders; and I do hereby declare the following to be a full, clear, and exact description of the invention, such as will enable others skilled in the art to which it appertains to make and use the same.

This invention relates to pail holders and is particularly adapted for use in holding pails utilized in supplying young calves with milk although it is not restricted to this particular use.

The object of the invention resides in the provision of a pail holder of the character named which can be easily attached to a desired supporting part and when not in use can be folded against such part out of the way.

With the above and other objects in view the invention consists in the details of construction and in the arrangement and combination of parts to be hereinafter more fully described and particularly pointed out in the appended claim.

In describing the invention in detail reference will be had to the accompanying drawings wherein like characters of reference denote corresponding parts in the several views, and in which—

Figure 1 is a perspective view of the holder with same in position to support a pail, the pail being shown in dotted lines; Fig. 2, a perspective view of the holder showing same folded against the supporting part, and Fig. 3, a sectional view through the bracket and the pivotal connection between the bracket and holding ring.

Referring to the drawings 10 indicates a suitable supporting part such as a wall, stall partition, etc. Secured to the supporting part 10 is a U-shaped bracket A including arms 11 and 12 and an arm connecting portion 13. The latter is disposed directly against the supporting part 10 and is secured by means of bolts 14. The arms 11 and 12 are connected by a pivot bolt 15 and a supporting bolt 16. The holder further comprises a ring 17 formed of a strip of metal and having its terminals directed laterally to produce arms 18 and 19 which latter are pivotally engaged upon the bolt 15. A sleeve 20 is mounted upon the bolt 15 between the arms 18 and 19 to prevent movement of said arms toward each other. When the device is not in use the ring 17 is swung to the position shown in Fig. 2 and when it is desired to support a pail it is moved to the position shown in Fig. 1, the arms 18 and 19 resting upon the bolt 16 and maintaining the ring in substantially horizontal position for the reception of a pail.

What is claimed is:—

A pail holder comprising a U-shaped bracket provided with means for attachment to a supporting part, pivot and supporting bolts connecting the arms of said bracket, a ring having lateral arms pivotally connected to the pivot bolt and adapted to rest on the supporting bolt when the ring is in supporting position, and a sleeve on the pivot bolt for preventing movement of the arms toward each other.

In testimony whereof, I affix my signature, in the presence of two witnesses.

ELMER A. SNELL.
